UNITED STATES PATENT OFFICE.

HERBERT A. NORTHROP, OF PALMER, MASSACHUSETTS; JOSIE M. NORTHROP
EXECUTRIX OF SAID HERBERT A. NORTHROP, DECEASED.

SCREEN.

1,123,136.

Specification of Letters Patent. Patented Dec. 29, 1914.

Application filed October 20, 1913. Serial No. 796,134.

To all whom it may concern:

Be it known that I, HERBERT A. NORTHROP, a citizen of the United States of America, residing at Palmer, in the county 5 of Hampden and State of Massachusetts, have invented a new and useful Screen, of which the following is a specification.

My invention relates to improvements in window screens, in which the screen fabric 10 is held in place over the entire window opening, on the outside, by means of top and bottom bars, without side bars, and consists of a screen comprising such fabric and top and bottom bars therefor, with certain peculiar retaining and fastening means therefor, all used in connection with a window frame, as hereinafter set forth.

The primary object of my invention is to provide an outside screen that is not only 20 cheap and simple in construction, but one that can be very easily and quickly put up and taken down, and when applied is securely held in place, does not interfere in any way with the movement of the window 25 sashes, and may be readily rolled for shipment or storage. With screens of this type heretofore made, the fastening means in order to be adequate for the purpose have been in the form of screws or other parts or 30 members that must be removed, in order to take down such screens, and so are very liable to become lost or misplaced. This is an undesirable and troublesome feature which I have entirely avoided by employing 35 fasteners that remain in place, either when the screen is in position over the window or removed from such position.

Other objects and advantages will appear in the course of the following description. 40 I attain the objects and secure the advantages of my invention by the means illustrated in the accompanying drawings, in which—

Figure 1 is a perspective view from the 45 outside of a practical form of embodiment of my invention; Fig. 2, a vertical section through the same, and, Fig. 3, an enlarged elevation of one of the fasteners provided to secure the screen to the window casing or 50 frame.

Similar figures refer to similar parts throughout the several views.

In the first two views a window frame is represented at 1 and a sill at 2, both of ordinary construction. The screen, that is de- 55

signed to cover the opening in the aforesaid frame, consists of top and bottom bars 3—3 and a length of screen fabric 4 which is firmly attached at its ends, by any suitable means, to said bars on the inside, so that 60 such fabric comes next to the outside face of said frame. The fabric 4 is wide enough to lap over the side edges of the frame opening, and long enough, with the added width in part of the bottom bar 3 at least, to completely cover said opening lengthwise. Each bar 3 is longer than the width of the frame opening, and preferably longer than the width of the fabric 4, so as to afford ample 65 bearings for a pair of fasteners 5, which both support and confine said bar at its projecting terminals, and also to afford ample bearing surfaces to engage the sides of the frame 1, especially in the case of the bottom bar.

There is a pair of fasteners 5 for each bar 3, those of the upper pair projecting from the outside face of the frame 1 at points adjacent to the upper corners of the frame opening, at the right and left respectively of 70 such corners, and each of those of the lower pair of such fasteners projecting from such face directly in line with one of those above, and being located above the sill 2 at a distance which is equal to the width of the 75 bottom bar 3. Each fastener 5 consists of a screw-threaded shank 6 which is adapted to be screwed into the frame 1, and a head 7 which is in angular relation to such shank. Preferably the head 7 stands outwardly a 80 little from the perpendicular, or forms an obtuse rather than a right-angle with the shank 6. The purpose of this is to facilitate the engagement and disengagement of the parts, and to cause the heads 7 to bear at 85 their inner terminals more firmly on the bars 3, than at their outer terminals, whereby is produced a wedging effect or cam action. This latter effect or action is desirable, because the pull of the fabric 4 tends 90 to force the top and bottom or outer longitudinal edges of the bars 3, taken as a pair, against the frame 1, and it is quite desirable not to say necessary that the inner edges of such pair be also held or forced against 95 the frame. As previously intimated, the outward inclination of the free ends of the heads 7 makes it easy to slip the top bar 3 into place and to fasten the bottom bar 3, in 100 the manner presently to be described. The 105

shanks 6 of the upper pair of fasteners 5 are set into the frame 1 just far enough to leave projecting only enough of such shanks to receive the upper bar 3 between said frame 5 and the heads 7 of said fasteners, and the same thing is substantially true of the under pair of fasteners 5.

In placing the screen, which is usually rolled when not in use, in position, the outer 10 bar 3 of the roll, or in any event one of the bars 3, is first placed on the upper pair of fasteners 5, if necessary being crowded down onto the shanks of such fasteners behind the heads of the same. Then the other bar 3, 15 after unrolling the screen if rolled, is forced down to make the fabric taut and pressed under the shanks of the lower fasteners 5, while the latter have their heads turned outwardly, as represented by dotted lines at 20 8—8 in Fig. 1. And finally the lower fasteners are turned to bring their heads down in front of the bottom bar 3. The bars 3 are now held securely by the four fasteners against the frame, the frame opening is fully 25 covered. The bottom bar 3 is held by the lower fasteners 5 on the sill 2 or between said sill and the shanks of said fasteners, hence there is no liability that said bar will be displaced. To remove the screen, simply 30 turn the lower fasteners so that their heads are out of the way of the bottom bar and attached fabric, draw said bar from beneath said fasteners, and with the hand or a stick or other implement lift the top bar out of 35 engagement with the upper fasteners, the screen being meanwhile rolled up if desired.

I have included the window frame in the description of my invention, because the same is necessarily an element therein. The 40 screen is in a sense incomplete without the window frame, and without such frame and my particular fastening means there is no invention, since screens consisting of two bars and an intervening screen fabric are 45 old in the art.

What I claim as my invention, and desire to secure by Letters Patent, is—

1. The combination, in a window screen, with a window frame, and two pairs of fasteners respectively projecting from the upper and lower portions of said frame, each of such fasteners consisting of a shank and a head in angular relation to said shank, of two bars, and a length of screen fabric attached to such bars and of a width which is less than the length of either of such bars, the latter being adapted respectively to be received on the shanks of the upper pair of said fasteners and under the shanks of the

lower pair of said fasteners, with the heads 60 of said fasteners in front in all cases, and adapted to counteract the pull of the fabric on the bars and with said fabric to force said bars tightly against the window frame.

2. The combination, in a window screen, 65 with a window frame, and two pairs of fasteners respectively projecting from the upper and lower portions of said frame, each of such fasteners consisting of a shank and a head arranged in obtuse-angular relationship, of two bars, and a length of screen fabric attached to said bars and of a width which is less than the length of either bar, 70 said bars being adapted respectively to be received on the shanks of the upper pair of 75 said fasteners and under the shanks of the under pair of said fasteners, with the heads of said fasteners in front and in binding relation at their inner or base terminals with the contiguous edges of said bars.

3. The combination, in a window screen, 80 with a window frame, and two pairs of fasteners respectively projecting from the upper and lower portions of said frame, each of such fasteners consisting of a screw-threaded shank and a head arranged in obtuse-angular relationship, of two bars, and a length of screen fabric attached to said bars and of a width which is less than the length 85 of either bar, said bars being adapted respectively to be received on the shanks of the upper pair of said fasteners and under the shanks of the under pair of said fasteners, with the heads of said fasteners in front 90 and in binding relation at their inner terminals with the contiguous edges of said bars.

4. The combination, in a window screen, 95 with a window frame, and two pairs of fasteners respectively projecting from the upper and lower portions of said frame, each of such fasteners consisting of a shank and a head in angular relation to said shank, of two bars, and a length of screen fabric 100 attached to such bars, the latter being adapted respectively to be received on the shanks of the upper pair of said fasteners and under the shanks of the lower pair of said fasteners, with the heads of said fasteners in front in all cases, and the fasteners in said 105 lower pair being adapted to be turned aside for the reception of said lower bar, and when turned down to have a cam action effect on said lower bar.
